FRANK AUGUST HALVERSON, OF GLEN RICHEY, PENNSYLVANIA

BLASTING DEVICE

Application filed September 8, 1928. Serial No. 304,826.

The present invention relates to improvements in blasting devices and more particularly refers to an improved pellet powder firing tube with automatic air cushion shot attachment.

An object of the invention is to provide an improved blasting device which will insure a safe and unfailing detonation with squibs, electric squibs and electric blasting caps in all types of shooting operations.

A further object of the invention resides in providing an extremely simple device for the above purpose in which economy in the use of material is promoted.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side view, partly broken away, of the improved device shown as in place ready for use.

Figure 2 is a longitudinal section.

Figure 3 is a cross-section taken on the line 3—3 in Figure 2, and

Figure 4 is a cross-section taken on the line 4—4 also in Figure 2.

Referring more particularly to the drawings, which show only one embodiment of the invention, 5 designates a blasting tube, hollow to receive the squib or fuse (not shown), and having one end 6 beveled, for insertion in the bore 7 of the pellet or powder charge 8. The tube 5 extends from the pellet, which is lodged in the base of the bore hole 8, to the mouth of such bore hole, where it is accessible for setting off the charge. The stemming material, indicated at 10, is used to fill the bore 9 following the usual practice.

A barrel 11 is mounted over the tube and is preferably welded or otherwise affixed to the tube at a distance from one end thereof in

order to provide a shoulder against which the pellet 8 may engage.

On the barrel and spaced from the ends thereof are rings 12 and 13, themselves spaced apart and acting to confine the adjustable collar, which is preferably made up of the two washers 14 and 15 welded or otherwise secured together for mutual reinforcement. The collar has a limited axial movement on the barrel, between the rings and is frictionally fitted to the barrel whereby to remain in adjusted position. In Figure 1 is shown an air cushion space 16 lying between the collar and pellet.

In operation, the end 6 of the blasting tube 5 is inserted, say for about four inches, into the round center hole 7 of the pellet, and the pellet is pushed firmly against the adjacent end of the barrel 11, which is say four inches long. The barrel will hold the pellet in place. Thereupon insert the pellet, so affixed to the tube, into the bore hole 9 and push it back to the end of the hole, as shown in Figure 1. The collar 14, 15 is adjusted along the barrel, to the required position for giving the desired length of cushioning air space or gap 16, before inserting the device in the bore hole. When the device is moved to final position the stemming 10 is introduced by use of a copper tipped or other tamping bar with the groove of the bar placed against the blasting tube 5. The collar 14, 15 acts as an abutment to arrest the stemming and to provide the space 16, which may be two or three inches in length. A squib is placed in the hollow tube 5 and lighted, whereupon such squib will run backward into pellet powder 8 through a clear passage, and shot will instantly follow.

In shooting pellet powder today with squibs, miners and shot firers experience trouble in pushing the pellet back because of the miner's needle being small and the pellet will not go to back of hole without being broken—with the blasting tube this could not happen, as the cushion attachment is larger than the

firing hole in the pellet and will hold the pellet from slipping back when being inserted. In stemming the hole under present methods, miners break the pellet when back with the tamper and pulverize it, in order to insure "soft powder" for the squib to ignite. This is a dangerous practice and it makes really two explosives in one shot. The fine dust of pellet will "flare" an instant before the solid pellets are ignited and part of the explosive force is lost and of no value. Furthermore, an excessive amount of smoke is created. In addition, in pulling the needle out of the hole through the stemming, the point of the needle will oft-times become bent by the heavy tamping bar and, of course, a bent needle point will cause part of the stemming to fill the hole so the squib's progress into the pellet is blocked and the shot is not fired.

This means loss of time, loss of labor and loss of powder to the miner. Anything of this nature could not happen when the blasting tube was used as the hole in the tube would insure a clear passageway for the squib into the pellet and the cushion attachment would stop the tamping from breaking the pellet into dust in the stemming.

The cushioned effect of all shooting is universally recommended by mining men because of its non-shattering effect on coal and other material and the barrel arrangement with collar and rings to hold it and to make it adjustable to whatever distance is required to secure best results can easily be arranged to local conditions. Also the collar will hold the stemming from crushing the pellet into dust.

All of the parts are preferably of copper to comply with the rigid mining law.

It is obvious that various changes and modifications may be made in the details of construction and design of the above specifically described embodiment of this invention without departing from the spirit thereof, such changes and modifications being restricted only by the scope of the following claims:

What is claimed is:—

1. An improved blasting device comprising a tube having one end adapted to be fitted into the bore of a pellet and adapted to receive squib, a barrel on the tube spaced from the inserted end of the tube and abutting against the end of the pellet, and an adjustable reinforced collar on the barrel for receiving thereagainst the stemming to form an air cushion space between the pellet and stemming.

2. An improved blasting device comprising a tube having a beveled end to penetrate powder pellet charge, a barrel on the tube abut against the pellet, spaced rings on the barrel, and a collar frictionally and adjustably mounted on the barrel to form an abutment for the stemming and a cushioning space adjacent the powder charge.

3. An improved blasting device, compris-

ing a long tube, a barrel secured on the tube in spaced relation to the inner end thereof, said tube adapted to be inserted at its inner end into a pellet or charge to an extent limited by the adjacent end of the barrel and introduced therewith into the bore made for blasting, and a collar mounted on the barrel for adjustment toward and from the inner end thereof to vary the air cushion space in front of the pellet, said collar adapted to receive the stemming thereagainst and the tube adapted to receive the usual squib.
